UNITED STATES PATENT OFFICE.

FRANK HARGREAVES HILLIARD, OF FITZGERALD, GEORGIA, ASSIGNOR OF ONE-HALF
TO HARMAN L. SMITH, OF FITZGERALD, GEORGIA.

TOOL.

1,377,348.

Specification of Letters Patent. Patented May 10, 1921.

Application filed January 2, 1920. Serial No. 348,834.

To all whom it may concern:

Be it known that I, FRANK H. HILLIARD, a citizen of the United States, and a resident of Fitzgerald, in the county of Ben Hill and 5 State of Georgia, have invented certain new and useful Improvements in Tools, of which the following is a specification.

My invention is an improvement in tools, and has for its object to provide a tool especially adapted for use with motor vehicles, 10 wherein a blade is provided having a handle provided with an offset portion, forming a stop, for permitting the tool to be used as a jack pedal, the blade being adapted for moving dirt, or the like, and having openings of 15 polygonal outlines to permit the tool to be used as a wrench, the handle or blade serving also to assist in the removal or replacement of a tire.

20 In the drawings:

Figure 1 is a side view showing the tool in use as a jack pedal,

Fig. 2 is a similar view showing its use as a wrench, and

25 Fig. 3 is a perspective view of the improved tool.

In the present embodiment of the invention, the improved tool comprises a blade 1 and a handle 2, which has the free end 30 thereof offset laterally from the plane of the blade and handle as shown at 3 to form a stop 4 at the junction of the offset portion with the body of the handle.

Referring to Fig. 3 it will be seen that the 35 handle or shank of the tool is gradually reduced from the blade to the free end, and that the edge of the blade remote from the

handle is beveled as shown at 5, to provide a scraping or cutting edge. The blade has a series of openings 6 of different size, and 40 polygonal in outline, as for instance hexagonal, for engaging the nuts, the tool thus serving as a wrench.

In use as a jack pedal, the offset portion 3 of the handle is introduced into the socket 45 7 of the jack 8, with the blade in nearly horizontal position as shown in Fig. 1, and the said blade may be engaged by the foot to operate the jack from the standing position.

In use as a wrench, the openings are engaged with the nuts 9, the device being especially adapted for releasing the holding lugs 10 to demountable rims. The blade may be used as a scraper, or for shoveling dirt, and either the blade or the handle may be used as 55 a tire tool to assist in replacing or removing rims.

The improved tool is extremely simple, may be cheaply manufactured, and serves a variety of purposes in connection with a 60 motor vehicle.

I claim:

A jack operating tool comprising an integral metallic structure including a flat rectangular blade having extending from one 65 end thereof an elongated reduced portion constituting a handle, said handle having its free end offset to define a shoulder, the handle being insertible into a jack structure with the shoulder serving as a stop to limit 70 the degree of insertion, and said blade serving as a foot pedal.

FRANK HARGREAVES HILLIARD.
